UNITED STATES PATENT OFFICE.

JOSEPH H. BAMBERG, OF TOLEDO, OHIO, AND HERMAN H. DOEHLER, OF BROOKLYN, NEW YORK, ASSIGNEES TO DOEHLER DIE-CASTING COMPANY, OF BROOKLYN, NEW YORK, A CORPORATION OF NEW YORK.

CASTING APPARATUS.

1,271,993.

Specification of Letters Patent.

Patented July 9, 1918.

Application filed March 26, 1917. Serial No. 157,387.

To all whom it may concern:

Be it known that we, JOSEPH H. BAMBERG and HERMAN H. DOEHLER, both citizens of the United States, residing, respectively, at 5 Toledo, county of Lucas, State of Ohio, and the borough of Brooklyn, city of New York, county of Kings, and State of New York, have jointly invented certain new and useful Improvements in Casting Apparatus, of 10 which the following is a specification, reference being had therein to the accompanying drawings, which form a part thereof.

Our invention relates to casting apparatus, and more particularly to a type of apparatus 15 for use in producing semi-finished castings, as distinguished from so-called finished castings.

In semi-finished castings, the outside dimensions of the castings are sufficiently 20 oversize to permit machining or hand finishing. Apparatus made in accordance with our invention is designed to produce castings having a deep chill on the outer face thereof, the metal of the body of the casting being of substantially the same density 25 throughout, and being of graduated hardness from the outside thereof, to the inside. Apparatus made in accordance with our invention is especially adapted for use in 30 producing castings of white metal alloys having fairly high fusing points, such as aluminum alloys. To secure the desired chilling of the outer face of the casting, the main mold parts are made of metal having 35 the mold cavity and ingate or ingates therein while the core is composed of porous, fragile, refractory material thus limiting the radiation to the outside of the casting, and permitting a free venting from the inside 40 thereof. Ordinarily, the metal mold parts are heated to prevent a too rapid chilling action both about the ingate and about the wall of the mold cavity. Our present invention relates more particularly to the 45 portions of a casting apparatus consisting of the core structure and the co-operating portions of the mold parts, whereby the inside core will be accurately and automatically centered with relation to the mold cavity, in the movable mold parts and likelihood of a loss in 50 the alignment of the inside core through the breakage thereof, in closing the molds will be avoided. Furthermore, in apparatus made in accordance with our invention

the quantity of the frangible material embodied in the core, is reduced to a minimum and cores may be readily handled with sufficient rapidity to contribute toward an economical operation of the apparatus. 55

The essential characteristic of our invention is a rigid core base formed of non-frangible material, preferably metal adapted to have molded upon the outer facing thereof, the porous, frangible, refractory material, the contour of which conforms to the 60 opening to be formed on the casting. The thickness of this facing will be sufficiently great to permit the core base to be drawn from the casting, said facing breaking down upon the drawing of the core, in a manner 65 to permit the formation of undercuts in the casting. The extremity of the base, when material projections are formed in the casting, must be reduced so as to clear these 70 projections when drawing the core. 75

It is preferable to provide the outside of the base with a plurality of irregularities, which permit the outer facing to anchor upon the core base, in a manner to avoid 80 the displacement thereof in handling. 80

To permit a free venting of the mold cavity through this core, the base is made hollow to provide a plurality of ducts through which gases may readily pass. The facing 85 above referred to is applied only to that portion of the base which, when the mold is closed, projects within the mold cavity.

The invention consists in such novel features of construction and combination of parts, as are hereinafter set forth and described and more particularly pointed out in 90 the claims hereto appended.

Referring to the drawings,

Figure 1 is a plan view of a casting apparatus embodying our invention; 95

Fig. 2 is a side elevation of one of the mold sections showing the inner face thereof and the details of the base;

Fig. 3 is a section on the line 3-3 of Fig. 2;

Fig. 4 is an enlarged detail view, and

Fig. 5 is a section on line 5-5 of Fig. 4.

Like letters refer to like parts throughout the several views.

In the embodiment of our invention 105 shewn in the drawings, *a* indicates a support or base for the movable mold parts *b-c*, said support and said mold parts being pro-

vided with coöperating means, as the tongue and groove a' for guiding the movement of said mold parts in opening and closing the mold. The support a is also provided with 5 an annular groove a^2 to admit air under the mold parts and prevent suction interfering with the free sliding movement thereof, while at the same time, forming a receptacle into which fragments of the core facing 10 falling upon the support or base a will be deposited when moving the mold parts, to prevent displacement of these parts or clogging thereof.

Each of the mold parts $b-c$ has a part of 15 a mold cavity therein, or when two castings are formed in the same apparatus, two such portions of a mold cavity as $d-d'$ spaced apart, and in alinement with each other, a well as e being formed between the adjacent 20 open mouths of said cavities. The mold parts $b-c$ are made of metal or other material having high heat conductivity.

Extending about the ends of each of the 25 mold cavities $d-d'$ respectively are semi-circular depressions forming together supplemental ingates g and g' leading into which respectively are ingates h and h' , each disposed upon opposite sides of the line of parting of the mold parts to facilitate 30 the drawing of the sprue with the finished casting. These ingates are constricted toward the supplemental ingates to facilitate the separation of dross and insure only clean metal entering the mold cavity. The 35 ingates enter adjacent the top of the supplemental ingates to permit the metal to build up from the bottom of the mold cavity.

Slidably mounted in suitable beamings 40 $i-i'$ extending axially of the mold cavities $d-d'$, and formed of two halves carried by the sections $b-c$ respectively, are metal cores $J-J'$ provided with operating handles J^2-J^3 respectively. These cores are accurately positioned by means of their enlarged 45 heads J^4-J^5 , and the stop pins J^6-J^7 which prevent their accidental displacement while the mold is being filled. Other movable cores for forming openings through the 50 wall of the casting and slidably mounted in the molds parts $b-c$ are shown at J^8-J^9 .

The mold parts $b-c$ are adapted to be locked in the closed positions by means of the metal straps $k-k'$ pivoted upon studs 55 k^2-k^3 and carrying similar studs k^4-k^5 , by which cams k^6-k^7 are carried, the cams being movable into engagement with lugs $s-s'$, for forming a tight joint at the line of parting of the mold parts.

60 The support or base a is provided with a pedestal f , which when the mold is closed, is adapted to project within the well e and engage the walls thereof in a manner to accurately position the two mold parts $b-c$ when the mold is closed. This pedestal also

serves as a support for the inside core in preparing for, and during, the casting operation.

The inside core is formed of a metallic or other non-frangible body having the portion, or portions, thereof projecting within the mold cavity $d-d'$ provided with a facing of porous, frangible, refractory material, such as sand or a plastic composition conforming to the opening to be found upon 75 the inside of the casting. The body of this core, in the form of the invention shown, consists of a central portion m adapted to seat upon the pedestal f , a dowel pin and socket connection f' being provided for the 80 purpose of securing approximate accuracy in the positioning of the portion m . Projecting from this portion m are two cylindrical extensions $n-n'$ the end faces of which are adapted to project inwardly 85 across the end of the mold cavities $d-d'$ so as to have the metal at this point, cast against this core. The peripheries of the extensions $n-n'$ are adapted to be engaged by the outwardly flared circular mouth portions $o-o'$ of the mold parts $b-c$ in a manner to cause the engagement of this portion of said mold parts respectively with said extensions $n-n'$, to accurately center the 90 core with relation to the mold cavities, the dowel pin and socket connection f' between the portion m and the pedestal f being sufficiently loose to permit that slight shifting of the core necessary to secure the automatic adjustment thereof in closing the 95 mold. The portion m is provided with a register socket p adapted to coöperate with a pin p' upon the pedestal f , for the purpose of insuring the proper core base being used in relation to the proper mold cavity. 100 This pin and socket connection also has sufficient play to permit the automatic adjustment of the core in the manner above referred to.

Extending axially of the extensions $n-n'$ 110 respectively, are core bases adapted to receive the facing of refractory material above referred to. The contour of these bases differs with different castings, but will possess the general characteristics of being rigid and non-refractory, while having openings therethrough to permit the escape of gases. Each of these bases comprises an extension q of smaller dimensions than the extensions $n-n'$ from which it projects, the 115 dimensions of this projection being smaller than the smallest inside dimensions of the cavity to be made, throughout that portion of the mold cavity into which the projections extend. Extending axially of said extension q is a reduced end q' the dimensions of this end being such as to permit the outer end of said base to clear metal cores in projections upon the inside of the casting, in a 120 manner to permit the rapid drawing of the 130

core, either from the refractory facing or from the completed casting, so as to allow free shrinkage of the casting in its entirety without likelihood of the development of 5 cracks, concealed, or otherwise, in the casting. Ordinarily the drawing of this core will result in the breaking down of the facing material.

The base for the core facing, which facing 10 is indicated at *r* in the accompanying drawings, is of graduated or of gradually reduced dimensions toward the end thereof. This base does not have any function in forming the inside of the casting, but serves 15 merely as a support for the facing material which is molded upon this base. The projections *q*—*q'* are provided upon the exterior thereof, with a plurality of overhung ribs *q*² by means of which the facing is anchored to the base; and extending through said base are a plurality of vent openings *q*³, the aggregate capacity of which is such as to permit the free escape of gases from the mold cavity, through the body of said 25 facing material and said openings.

The projections *q*—*q'* and the extensions *n*—*n'* are hollow to facilitate the escape of the gases therethrough.

The mold parts *b*—*c* are provided with 30 suitable air spaces about the walls of the mold cavity to facilitate the radiation of heat therefrom.

The operation of the herein described apparatus is substantially as follows:—

35 The mold parts *b*—*c* are first brought by any suitable means, to a temperature which will prevent such a rapid chilling of the inflowing metal as will interfere with the proper filling of the mold cavity and cause 40 the formation of surface flaws thereon. The two parts *b*—*c* are then separated and the inside core, formed as described, is deposited upon the pedestal *f*, the socket *p* being brought about the pin *p'* so as to insure the 45 proper extensions *q*—*q'* entering the mold cavity in connection with which they are designed to be used.

The construction of the inside core is such 50 that metal portions thereof may be used in handling it, and the body portion *m* being of metal, likelihood of the breaking of the portions of the core formed of sand, plaster or other frangible material is reduced to a minimum. The dowel pin and socket connections *f* will insure substantial accuracy 55 in the positioning of the core.

When the core has been properly positioned upon the pedestal *f*, the mold parts *b*—*c* are closed by a sliding movement upon 60 the base *a* until the portion of the wall of the well *e* formed in the face of each mold part, contacts with the pedestal *f*, thus positioning the mold cavities in said mold parts with approximate accuracy in relation to the 65 inside core. As the mold parts are closed,

the beveled portions *o*—*o'* about the mold cavities, engage the peripheries of each extension *n*—*n'* upon the core body *m*, and impart such movement to the core in its entirety as may be necessary to bring the extensions *q* and reduced ends *q'* into axial alinement with the mold cavity. This automatic adjustment of the core may be a slight rotative movement of the core body *m* about the dowel pin and socket connection *f*', or 70 it may be a movement longitudinally of the apparatus, or it may be both. The effect of this adjustment is that the inside core will always be positioned alike during succeeding casting operations, with a resultant 75 identity in all castings produced.

When the mold is thus closed, the two parts thereof are locked together by means of the clamp mechanism above described, and metal is poured from a ladle through 80 the main ingates *h*—*h'* and supplemental ingates *g*—*g'*.

The casting builds up from the bottom of the mold cavity, the molten metal flowing from the supplemental ingate directly to 90 every portion of the mold cavity.

That portion of the metal forming the outside of the casting, contacts with heated metal, so that a slow chilling action occurs as to this part of the casting. The portions 95 of the metal forming the inside of the casting, contact with the facing *r* upon the core base portions *q*—*q'*, so that a chilling of the inner face of the casting is prevented.

While suitable vents about the mold cavity are provided, the porosity of the core facing and the openings through the core base *q*—*q'* will permit a free venting 100 through the core.

Castings made in accordance with our invention have the characteristics, by reason of the control of the radiation of heat, that the outer face thereof has a deep chill and the casting is of graduated hardness from this outer face toward the inner face thereof 105 which has little or no chill. Furthermore, since the casting shrinks upon the core, instead of upon itself, the metal throughout the casting will be of substantially uniform density throughout, and will not be stratified, or have any line of demarcation between the metal adjacent opposite faces of 110 the casting.

After the mold cavity is filled, sufficient time is allowed to elapse before opening the 120 mold, to allow for the initial solidification of the metal of the casting. The outside cores *J*—*J'*—*J*^s—*J*^p are then drawn and the mold opened, the castings remaining upon the core bases *q*—*q'* and continuing to 125 shrink upon the facing of these bases. When the metal is properly conditioned, the castings are drawn from the ends of said bases, the said facing breaking down about under cuts, or projections within the cast- 130

ing. Since the bases $q-q'$ are of reduced dimensions from the extensions $n-n'$ toward their ends, the metal portions of the core do not interfere with the drawing of 5 the casting, or of the core.

The interlock between the core bases and the facings thereof, prevents any shifting of the facing material circumferentially of the said base. While the openings in said base 10 may become filled with the facing material, this will not interfere with the passage of the gases through these openings.

While in the accompanying drawings, we have shown an apparatus especially adapted 15 for casting cylinders for internal combustion engines, our invention is not limited to the character of casting made therein, since the apparatus may be made to cast any hollow, cup-shaped or other object requiring an 20 inside core.

Having described the invention what we claim as new and desire to have protected by Letters Patent is:—

1. A casting apparatus embodying therein 25 a plurality of metal mold parts capable of relative movement to open and close the apparatus, each of said parts having a portion of a mold cavity and of an ingate formed therein, a support for said mold parts, 30 means carried thereby, whereby an inside core may be supported within said mold cavity, and an inside core comprising a non-frangible body, a core base carried thereby and projecting therefrom into said mold 35 cavity, and a facing upon said core base formed of porous, refractory material.

2. A casting apparatus embodying therein 40 a plurality of metal mold parts capable of relative movement to open and close the apparatus, each of said parts having a portion of a mold cavity and of an ingate formed therein, a support for said mold parts, 45 means carried thereby, whereby an inside core may be supported within said mold cavity, and an inside core comprising a non-frangible body, a hollow core base carried thereby and projecting therefrom into said mold cavity, said core base having vent 50 openings therethrough, and a facing upon said core base formed of porous, refractory material.

3. A casting apparatus embodying therein 55 a plurality of metal mold parts capable of relative movement to open and close the apparatus, each of said parts having a portion of a mold cavity and of an ingate formed therein, a support for said mold parts, 60 means carried thereby, whereby an inside core may be supported within said mold cavity, and an inside core comprising a non-frangible body, a core base carried thereby and projecting therefrom into said mold cavity, said core base being of 65 gradually reduced dimensions from said core body toward the end of the base, and a

facing upon said core base formed of a porous, refractory material.

4. A casting apparatus embodying therein 70 a plurality of metal mold parts capable of relative movement to open and close the apparatus, each of said parts having a portion of a mold cavity and of an ingate formed therein, a support for said mold parts, means carried thereby, whereby an inside core may be supported within said 75 mold cavity, and an inside core comprising a non-frangible body, a hollow core base carried thereby and projecting therefrom into said cavity, said core base having vent openings therethrough, said core base being of gradually reduced dimensions from 80 said core body toward the end of the base, and a facing upon said core formed of porous, refractory material.

5. A casting apparatus embodying therein 85 a plurality of metal mold parts capable of relative movement to open and close the apparatus, each of said parts having a portion of a mold cavity and of an ingate formed therein, a support for said mold 90 parts, means carried thereby, whereby an inside core may be supported within said mold cavity, an inside core comprising a non-frangible body, a core base carried thereby and projecting therefrom into said 95 mold cavity, and a facing upon said core base formed of porous, refractory material, and means for automatically adjusting said inside core with relation to said mold cavity comprising a cylindrical extension upon 100 said core body and a coöperating beveled portion upon said mold parts extending about the end of the mold cavities therein.

6. A casting apparatus embodying therein 105 a plurality of metal mold parts capable of relative movement to open and close the apparatus, each of said parts having a portion of a mold cavity and of an ingate formed therein, a base upon which said mold parts are slidably mounted, a pedestal carried by said base at one side of the mold cavity in said parts, said parts having recesses therein forming a well, the wall of which is adapted to engage said pedestal 110 when the mold parts are closed, and an inside core comprising a core body adapted to seat upon said pedestal, a core base carried thereby and projecting therefrom into said mold cavity, and a facing upon said core base formed of porous, refractory material. 115

7. A casting apparatus embodying therein 120 a plurality of metal mold parts capable of relative movement to open and close the apparatus, each of said parts having formed therein portions of a plurality of mold cavities, ingates, and a well intermediate said mold cavities, a base upon which said mold parts are slidably mounted, a pedestal upon said base, adapted to occupy said well when 125 the mold parts are closed, an inside core 130

comprising a core body adapted to seat upon said pedestal, a plurality of hollow core bases having openings therethrough projecting from said core body into said mold 5 cavities respectively, and a facing upon each of said core bases formed of porous, refractory material, a dowel and socket connection having lost motion therein, between said pedestal and said core body, a coöperating 10 guide pin and socket upon said pedestal and said core body, whereby said core bases will always coöperate with the same mold cavity, and means for automatically adjusting said inside core with relation to said mold cavity 15 comprising a cylindrical extension upon said core body and a coöperating beveled

portion upon said mold parts extending about the end of the mold cavities thereln.

In witness whereof, we hereunto affix our signatures, in the presence of two subscribing witnesses, this 14th day of March, 1917, as to BAMBERG, and this 23d day of March, 1917, as to DOEHLER. 20

Correction in Letters Patent No. 1,271,993.

It is hereby certified that in Letters Patent No. 1,271,993, granted July 9, 1918, upon the application of Joseph H. Bamberg, of Toledo, Ohio, and Herman H. Doehler of Brooklyn, New York, for an improvement in "Casting Apparatus," an error appears in the printed specification requiring correction as follows: Page 1, line 37, for the word "fragile" read *frangible*; and that the said Letters Patent should be read with this correction therein that the same may conform to the record of the case in the Patent Office.

Signed and sealed this 6th day of August, A. D., 1918.

[SEAL.]

R. F. WHITEHEAD,
Acting Commissioner of Patents.

Cl. 22—126.
